UNITED STATES PATENT OFFICE

PAUL MAHIEU, OF PARIS, FRANCE

APPARATUS FOR MOLDING

Application filed December 6, 1930, Serial No. 500,617, and in France December 7, 1929.

The present invention has for its object to provide an improved apparatus for molding under pressure and is primarily characterized in that the pressure of the fluid acting on 5 the material to be molded is progressive.

This essential characteristic obviates the blow holes which generally form in castings made under pressure, due to the fact that the air contained in the mold has insufficient time 10 to escape completely by the joints of the mold or the vents.

In the process according to the invention, when the metal is admitted into the mold, a small regulable pressure is exerted thereon to facilitate merely its flow and a higher pressure is not placed on the metal until this has sufficiently filled the mold. The casting taking place at the beginning under a moderate pressure the air contained in the 15 mold has the necessary time to escape completely through the vents. Subsequently the high pressure, which may be varied, produces all its advantages. It makes the metal take up the smallest details of the mold and it compensates for shrinkage of the metal, which shrinkage is particularly noticeable in the 20 case of thick parts.

The annexed figure shows by way of example one embodiment of apparatus for carrying out the invention.

In this figure the crucible 1 contains the metal 2 maintained in a molten state by the hearth 3. The upper opening of the crucible closed by a tight cover 4 forms a kind of air bell, damping out rapid variations of pressure. The air or other fluid under pressure is admitted through the conduit 8, which is formed with an intake chamber 8'.

In the wall of crucible 1 is formed a silicon-shaped conduit 9 conducting the metal to the union or nozzle 10 receiving the mold.

To obtain progressive increase in the pressure use is made of an expansion or reducing device comprising an expansion chamber 17 45 closed by a diaphragm 18 which through the rod 19 controls the valve 20 disposed at the outlet of the conduit 8. The pressure regulating spring 20' is controlled by the lever 12 and it will be seen that progressive lowering 50 of this lever causes progressive increase

of the pressure in 17 and 15. On raising the lever 12 the finger 21 carried by it acts on a valve 22 establishing communication between 15 and 17 and the atmosphere.

It will be seen that when a mold is joined 55 to the nozzle 10 it is possible to start molding with a sufficiently low pressure, which may gradually increase, while a mold is being filled and to bring the pressure to the necessary final intensity when the mold is sufficiently filled by lowering the lever 12. When 60 the metal is sufficiently solid in the mold the lever 12 is raised to cause the crucible to communicate with the atmosphere, thus permitting 65 the metal to descend through the conduit 9 to the same level as that in the crucible. The mold may then be removed and the operation recommenced.

It is pointed out that applicant's device 70 differs from those of the prior art in being substantially automatic. When the valve 20 is opened by a depression of the lever 12, the air enters the crucible under an initial pressure and when this pressure rises to a certain point the back pressure in the expansion chamber 17, is exerted on the diaphragm 18, which is pressed outward against the pressure of the spring and automatically closes the valve 20, thus allowing the air under 75 moderate and initial pressure to act on the metal in the crucible. When sufficient action is deemed to have taken place and an increase of pressure required, the lever 12 is further depressed, thus opening the valve and the air, under increase of pressure, is admitted. 80 This increase of pressure may be regulated 85 through the operation of the lever.

It is obvious that the means described above is only given by way of example, and may be 90 varied to a large extent without departing from the characteristics of the invention.

What I claim is:

1. In a molding apparatus of the character described, a crucible having a contracted outlet leading to a mold, a conduit connected to the crucible for the admission of air under pressure, said conduit including an expansion chamber, an open port in said chamber leading to the crucible, a valve seating port in said chamber for admitting pressure thereto, 95
- 100

a diaphragm mounted in said chamber opposite said second port, a valve in said second port, having a stem connected to said diaphragm and means mounted on the outside of said chamber, and adapted to exert determinable amounts of pressure on said diaphragm.

2. In a molding apparatus of the character described, a crucible having a contracted outlet leading to a mold, a conduit connected to the crucible for the admission of air under pressure, having an intake chamber and an expansion chamber, and having a manually operable valve between said chambers to control the passage of air from the intake chamber, and means in a wall of said expansion chamber for automatically closing said valve when a determined back pressure has been built up in said expansion chamber.

20 In testimony whereof I affix my signature.

PAUL MAHIEU.
